ALBERT LOVIE, OF PHILADELPHIA, PENNSYLVANIA, ASSIGNOR OF
ONE-HALF OF HIS INTEREST TO CHARLES F. STEINBACH.

Letters Patent No. 85,016, dated December 15, 1868.

IMPROVED CURTAIN-FIXTURE.

The Schedule referred to in these Letters Patent and making part of the same.

To all whom it may concern:

Be it known that I, ALBERT LOVIE, of the city and county of Philadelphia, and State of Pennsylvania, have invented a new and useful Improvement in Curtain-Fixture; and I do hereby declare the following to be a full, clear, and exact description of the same, reference being had to the accompanying drawing, forming part of this specification, in which—

Figure 1 is a front elevation of the device illustrating my invention.

Figure 2 is a top view of the button, on which the cord runs.

Figure 3 is a side view of the button and screw-spindle.

Similar letters of reference indicate corresponding parts in the several figures.

My invention consists in so constructing the button and its supporting-frame, whereby they can be easily applied to each other, as also to allow the former to be uniformly guided and securely retained in position, as will be hereinafter more fully described.

In the drawings, A represents a-frame, which is to be secured to the frame-work of the window or other place where the fixture is necessary.

This frame is constructed of any suitable metal, cast or stamped with front flanges or ways, *a a*, two side-pieces, *b b*, and top and bottom connecting-pieces, *c c*, whereby is formed a vertical slot, *d*, which will extend, or partly extend, from the top to the bottom of the frame.

The side-pieces *b* are not absolutely necessary, but as they increase the strength of the frame, it will be well to employ them.

It will be perceived that the flanges *a* are in advance of the top and bottom-pieces, so that the rear of the frame forms a space or chamber to receive a screw-spindle, B, whose upper end has connected to it a button, C, by which the pulley-cord is held. Its free end passes through an opening in the lower cross-piece *c*.

The pulley-cord is readily tightened or slackened by means of a nut, D, which screws on the spindle B.

The upper portion of the slot *d* has two branch slots, *e e*, which communicate therewith, and form a T-shaped opening in the frame. These branch slots are formed by cutting away the upper ends of the flanges *a*.

The shank of the button C is constructed with shoulders, *f f*, whose width should be equal to that of the branch slots *e e*, previously described.

The part *g*, between the shoulders *f f*, must be equal to the space between the flanges *a*.

In order to apply the button to frame A, the lower end of the screw-spindle B is passed through the opening in the cross-piece *c*, until the shank of the button is in line with the open slots *e*. Now force the button back until its shoulder *f*, strikes the frame, and then push or pull it down towards the bottom of the frame, and afterwards apply the nut D. It will be found that the shoulders *f f* embrace both sides of the flange *a*.

The button is thereby held in position on the frame, and uniformly guided in its motions.

When the cord is passed over the button, it may be readily tightened to the necessary tension by the nut D, and slackened by the same means.

To disengage the button from the frame, the nut must be screwed off, and the button raised until its shoulders reach the slots *e*. Now draw the button forward and the spindle out of the opening in the bottom-piece *c*, of the frame, and the parts are separated from each other.

The shoulders on the shank may be formed by circular disks, secured to the shank, or of angular or other-shaped pieces, which will answer the same purpose, but it will be necessary to form the branch slots *e* to correspond thereto.

I do not lay claim to the screw-spindle, nor to the nut, nor to the arrangement of parts as shown by me, for it may be varied; but having described my invention,

What I do claim, is—

The shouldered button *c*, cast or formed with the screw-spindle B, in combination with the slotted frame A and nut D, when the parts are constructed and adapted to operate as herein represented and described.

To the above, I have signed my name, this 17th day of October, 1868.

ALBERT LOVIE.
